UNITED STATES PATENT OFFICE.

JOHN V. BELLI, OF CLIFTON, NEW JERSEY.

LOOSE-LEAF BINDER.

Application filed March 29, 1926. Serial No. 98,349.

The present invention is concerned with a loose leaf binding device which may have a wide range of utility for binding blank leaves or for filing either single leaves or folded letter sheets.

An object of the invention is to provide a device of this character so constructed that the leaves will be securely retained in position within the folder and arranged to facilitate the insertion or removal of the leaves when such insertion or removal is desirable.

A further object of the invention is to provide a spring pressed retaining plate for the leaves which may optionally serve as a tearing guide in the event that the device is used as a note book.

Further objects of the invention are to provide a loose leaf folder of simple, practical construction, which will be rugged, durable and efficient in use, neat and attractive in appearance, capable of housing letter sheets in compactly folded position, and a binder which may be manufactured and assembled with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a plan view showing the binder in open position, and the spring pressed retaining plate folded over to act as a tearing guide for a sheet of material.

Fig. 2 is a view partly in end elevation of Fig. 1, and partly in transverse section on the line 2—2.

While the folder of the present invention may be made of either flexible or stiff back form, I prefer to use a pair of stiff covers 10 and 11 connected to a stiff intermediate back 45 12 by the use of strips of hinging material, such as the canvas strips 13 which may be pasted over both the inner and outer faces of the backing element 12 and over the adjacent edges of the covers 10 and 11.

Backing element 12 is preferably formed with a pair of openings reinforced by eyelets 14. An eyelet is provided adjacent each end of the backing element 12 and the sheets of material to be filed indicated at 15 are necessarily of a width less than the distance between the eyelets.

Additional eyelets 16 may be formed in the cover 11 near the hinged edge thereof for a purpose which will be more fully hereinafter described.

The folder herein illustrated finds one of its preferred uses as a file folder for the letter sheets 15. When the sheets are received in the folder their intermediate portions are disposed along the line of the backing 12, and are engaged by one edge of a spring pressed retaining plate 17, the free edge 18 of which may conveniently serve as a tearing guide, as best seen in Fig. 1.

The retaining plate is preferably of slightly greater width than the sheets 15 which are received in the folder, and is formed at each edge with an integral tubular guideway 19. These guideways accommodate contractile coiled springs 20. One end of each coiled spring is anchored to a stud member passed through the eyelets 14. As shown in the drawings these stud members may conveniently include heads 21 of greater diameter than the eyelets, and eyes 22 projecting through the eyelets and engaged with the ends of the springs 20. The opposite ends of the springs 20 are hooked over lugs or ears 24 defined at the edges of plate 18 by recessing the plate edges at 25 and notching them at 26.

In assembling the device, the coiled springs 20 are attached to the studs, passed through the sleeves 19, and hooked over the lugs 24. When it is desired to insert a letter sheet 90 under the retaining plate 17, it is merely necessary to manually grasp the plate and pull it away from the backing member 12, springs 20 yielding so that sufficient clearance is provided under the plate for the insertion of a sheet.

The purpose of the eyelet 16 is to facilitate the filing of single sheets of a size slightly less than one of the covers of the binder. In this instance the studs will be 100 passed through the eyelets 16 and anchored to the springs 20, and the plate 17 will serve to yieldingly clamp the inner edge of single sheets (by which I mean sheets of half the size of those shown) against the cover 11, as 105 will be readily understood.

The principal reason for making the plate 17 relatively wide is so that it may be used as a tearing guide as shown in Fig. 1, where-in the line upon which one of the sheets 15 will be torn is indicated in dot and dash. The device is peculiarly efficacious as a letter

sheet filer, because it will permit the letter-heads to be readily thumbed over and exposed, and at the same time retain all of the letter sheets in compactly folded condition when the binder is closed. The ordinary letter file would be at least twice the size of the present folder.

While I have illustrated one of the preferred embodiments of the invention, various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. A filing folder of the class described including a pair of stiff covers, a stiff back hingedly connecting the covers, a plate disposed parallel to and adjacent the line of hinging of the covers, and springs acting on the ends of the plate and anchored to the folder to retain the plate spring-pressed into engagement with loose leaves in the folder, one of said covers having eyelets near the edges thereof adapted to receive anchoring devices for the springs.
2. A filing folder of the class described including a pair of stiff covers, a stiff back hingedly connecting the covers, a plate disposed parallel to and adjacent the line of hinging of the covers, and springs acting on the ends of the plate and anchored to the

folder to retain the plate spring-pressed into engagement with loose leaves in the folder, said back having eyelets in the ends thereof adapted to receive anchoring devices for the springs.

3. A filing folder of the class described including a pair of stiff covers, a stiff back hingedly connecting the covers, a plate disposed parallel to and adjacent the line of hinging of the covers, and springs acting on the ends of the plate and anchored to the folder to retain the plate spring-pressed into engagement with loose leaves in the folder, one of said covers having eyelets near the edges thereof adapted to receive anchoring devices for the springs, said back having eyelets in the ends thereof adapted to receive anchoring devices for the springs whereby the plate may be anchored to the back to grip the intermediate portion of double sheets or to the edge of a cover to grip the edge of single sheets.

4. A filing folder of the class described including a pair of hingedly connected stiff covers, contractile coiled springs secured to opposite edges of the folder adjacent the hinge, a paper clamping plate detachably connected to the ends of the springs and pressed thereby into clamping engagement with paper in the folder, said plate including integral sleeves at its ends receiving the intermediate portions of the springs and lugs aligned with the sleeves and to which the ends of the springs are anchored.

JOHN V. BELLI.
